FOREIGN PATENT DOCUMENTS

EP 0381821 10/1989

Primary Examiner — David Muller

Assistant Examiner — Nathan Johnston

(57) **CLAIM**

The ornamental design for a medical glove dispenser, as shown and described.

DESCRIPTION

FIG. 1 is a front elevation view of a medical glove dispenser showing our new design;

FIG. 2 is a rear elevation view thereof;

FIG. 3 is a left side elevation view thereof, a right side elevation view being a mirror image thereof;

FIG. 4 is a top plan view thereof;

FIG. 5 is a bottom plan view thereof;

FIG. 6 is a top front side perspective view thereof; and,

FIG. 7 is a cross-sectional view thereof taken along line 7-7 of FIG. 1.
